UNITED STATES PATENT OFFICE.

ELMER S. SEAVEY, OF JOHNSTOWN, PENNSYLVANIA.

ADJUSTABLE CLAMPING JOINT.

1,408,834.

Specification of Letters Patent. Patented Mar. 7, 1922.

Application filed June 16, 1920. Serial No. 389,349.

To all whom it may concern:

Be it known that I, ELMER S. SEAVEY, a citizen of the United States, and residing in the city of Johnstown, in the county of Cambria and State of Pennsylvania, have invented certain new and useful Improvements in Adjustable Clamping Joints; and I do hereby declare the following to be a full, clear, and exact description of the invention, such as will enable others skilled in the art to which it appertains to make and use the same.

My invention relates to certain new and useful improvements in adjustable joint connections, and more especially to clamp joints whereby two supporting elements such as two bracket arms or rods may be sustained in the desired position and adapted to be easily adjusted and held in their adjusted position by frictional contact.

One of the objects of my invention is to provide a very simple and effective form of clamp connection between two elements, the planes of which intersect, so that the elements may be readily shifted longitudinally relative to each other and as readily clamped so firmly in their adjusted positions that they can not be accidentally shifted therefrom.

Another object of my invention is to provide a clamp joint having means for clamping two elements in their longitudinally adjusted position, so constructed as to permit the elements to be rotated relative to each other so as to secure any desired angular adjustment of the elements without, however, releasing any of the pressure of the clamp, and without in any way affecting the clamping action.

A further object of my invention is to provide a construction in which two elements may be moved to any desired position vertically or horizontally by a slight push or pull, and so formed that the elements will remain in their adjusted position until moved again.

Another object of the invention is to provide a construction of this character in which the elements may be moved forward or backward to shorten or lengthen them relative to the pivotal center of the elements by slightly releasing the clamping pressure.

A further object of the invention is to provide a clamping joint in which the gripping or clamping power of a screw is used to simultaneously clamp both elements sup-

ported by the clamping joint, the device being so formed that the slackening or tightening up of this one screw will act to release both elements to permit of their longitudinal adjustment or will tighten up both elements.

Still another object of my invention is to provide a joint of this character in which a resilient clamping member is provided for clamping one of the two elements, the said element passing through the resilient clamping member which has split sides and a beveled contact face, for engaging the beveled face of the other clamping elements, which may be formed integral with the element or it may be a separate clamping member for holding the opposite element but being beveled on one side for engaging the beveled face of the resilient clamping member, and hold it in frictional contact therewith, by means of a clamping screw.

Having thus given a general description of my invention, I will now, in order to make the same more clear, refer to the accompanying two sheets of drawings in which like characters of reference indicate like parts:

Figure 1 is a side elevation of an electric light bracket illustrating one form of application for which my invention may be used.

Figure 2 is a side elevation of one of the clamping joints drawn on a larger scale than in Figure 1, and showing the bracket arms in cross-section.

Figure 3 is a vertical sectional elevation through the clamping joint taken at right angles to the bracket arms.

Figure 4 is a vertical sectional elevation through the clamping joint taken at right angles to the section shown in Figure 3.

Figure 5 is a transverse sectional elevation taken on the line V—V of Figure 2.

Figures 6, 7, 8 and 9 are vertical sectional elevations through clamping joints of slightly modified forms to the joints illustrated in Figures 1 to 5 both inclusive, the sections of the figures being drawn at right angles to the bracket arms.

Figure 10 is a vertical sectional elevation of the joint shown in Figure 9, but drawn at right angles thereto.

Figure 11 is a vertical sectional elevation of the resilient clamping member detached.

Figure 12 is a side elevation of the resilient clamping member.

Figure 13 is a top plan view of another modified form of joint in which I have illustrated it as supporting a spot light.

Figure 14 is a vertical sectional elevation through the clamping joint shown in Figure 13, the section being taken at right angles to the clamping post, attached to an automobile or other device, the arm of the lamp bracket being turned at an angle thereto.

Figure 15 is a vertical sectional elevation through another modified form of joint I may use.

Figure 16 is a side elevation of the joint shown in Figures 13 and 14, and Figures 17 and 18 are still other modifications in which the clamping bolts serve the purpose of the resilient clamping member.

Referring now to the characters of reference on the drawings; and especially to Figures 1 to 5 both inclusive, the numeral 1 indicates the base of a portable electric lamp bracket which is adapted to be placed upon a table 2, or any other desired position where it may be easily seated. The base 1 has a standard 3, extending therefrom which is mounted upon the base and rigidly attached thereto and has one of my improved clamping joints 4, adjustably attached thereto by means of a resilient clamping member 5, which is split as at 6 with cylindrical openings therein as at 7, through which the standard passes. This resilient clamping member has an outer beveled face 8 and an angular flanged inwardly projecting edge 9. Upon the beveled face of the resilient clamping member is mounted a pair of clamping washers 10 and 11, the inner washer 10 having its lower face beveled inwardly as at 12, for engaging the beveled outer face of the resilient clamping member 5.

A clamping bolt 13, having an enlarged portion 14, intermediate its ends, has an elongated hole therein as at 15 for the passage of one of the rods to be clamped. The bolt 13, has a head 16, for engaging the angular inwardly projecting flanged edges 9, of the resilient clamping member 5, and a reduced neck portion 17, between the head 16 and enlarged intermediate portion 14 of the bolt, which extends through an opening 18 in the resilient clamping member 5. The upper end of the bolt 13 is of reduced size in cross-section and is screw-threaded as at 21 to receive a nut 22, which may be of any approved type, as a hand-wheel, thumb-nut, or wing-nut as desired. The washers 10 and 11, and the enlarged portion 14 of the bolt 13 are keyed together at 23, so that the washers, bolt and nut will rotate together and will not have a tendency to unscrew the nut when the arms of the bracket are moved or rotated for adjustment.

24 indicates an adjustable bracket arm

which is supported in position by the joint 4, mounted on the standard 3. This bracket arm is passed through the elongated hole 15 in the bolt 13 and is clamped between the arc-shaped faces 25 of the washers 10 and 11, when the nut 22 is screwed tight upon the bolt and at the same time the beveled faces 8 and 12, of the resilient clamping member 5 and the washer 10 contact with each other forcing the arc-shaped jaws 26 of the cylindrical openings 7, into gripping engagement with the standard 3, or adjustable bracket arm, as the case may be reversed if desired, the standard 3 being clamped between the washers 10 and 11, and the adjustable bracket arm 24 can be held by the resilient clamping member 5.

At an intermediate position upon the bracket arm 24 is mounted another adjustable joint 4, for supporting an adjustable extension arm or clamping element 27, having attached thereto an electric light socket, lamp and shade as indicated at 28.

Where the adjustable joint 4 is mounted upon a bracket arm for supporting an extension arm as indicated in Figure 1, I prefer to have the extension arm clamped between the washers of the joint, although it can be held by means of the resilient clamping member if desired.

Referring to Figures 6 to 10 both inclusive in which I have shown clamping joints of slightly modified forms, but in which the clamping action of the joints is substantially the same as above described, especially the resilient clamping member, and in which the same reference numerals will be used as for Figures 1 to 5.

In Figure 6 the clamping bolt 13 is constructed without the reduced neck portion 17, and the washers 10 and 11 are not keyed together, otherwise the construction is the same.

In Figure 7, instead of using clamping washers 10 and 11, I use a single washer 29, split as at 30, the remaining portions of the joint being similar with the exception, that the key 23 is omitted.

In Figure 8, the clamping washer 10 is made longer and formed with an annular recess 31, for the reception of the end of a tubular collar or washer 32. In this joint I have also omitted the use of a key, as it is not an essential feature in any of the joints, for the reason that when the bracket arm or clamping element is passed through the bolt and clamped between the washers these parts will all have to rotate together whether the key is used or not. When the key is used however the gripping jaws of the washers and the elongated hole in the bolt are always held in alignment with each other, even if the bracket arm is removed from the joint.

In Figures 9 and 10 instead of using the two clamping washers 10 and 11 I have used

a single washer or tubular member 33, split as at 34, with transverse holes in the sides thereof as at 35, for the passage of the clamping element. The upper end of the washer 33 is beveled as at 36, for engaging the beveled underside 37 of the clamping nut 38. The upper part of the enlarged intermediate portion of the clamping bolt 13 is made conical as at 39, with a slight space as at 40, between the conical sides of the bolt and the upper end of the tubular washer 33, to allow the upper end of the tubular washer 33 to be forced inward when the nut is screwed tight upon the end of the clamping bolt for gripping the sides of the rod or element to be clamped. The clamping bolt also has a keyway formed therein as at 41, for receiving the end of a pin 42, extending into the keyway from the tubular washer 33.

20 Referring now to the modifications illustrated in Figures 13 to 18 both inclusive, in Figures 13, 14 and 16 of the drawings, 43 indicates a portion of a spot light or similar article, having a bracket arm 44, rigidly attached thereto, the outer end of which has an opening therethrough as at 45, for the passage of a bolt 46, an annular recess 47, for receiving the head 48, of the bolt 46, and an annular beveled face 49, surrounded by a flanged edge 50.

25 51 indicates the resilient clamping member having a central opening 52, and beveled outer faces 53 and 54, the beveled face 53 engaging the beveled face 49 on the arm 44, and the beveled face 54, contacting with the beveled edge 55 of the washer 56.

30 The attaching member of the bracket comprises a two-part clamp, one of the parts being indicated by the numeral 57 and the other by the numeral 58, and these parts are 40 provided each with a jaw portion indicated by the numeral 59, and the parts are further provided with openings through which is passed a clamping bolt 60, having a nut 45 61 threaded thereon.

35 By reference to Figure 13 of the drawings it will be understood that when the parts 57 and 58 are properly assembled with the jaws 59 thereof engaging opposite sides of the 50 frame of a wind shield or any other part of the vehicle suitable for the support of the spot light, the nut 61 may be tightened so as to firmly clamp the parts in place and the attaching member will then be rigidly held 55 with relation to the portion of the vehicle to which it is applied. The member 57 is provided with a laterally extending cylindrical post 62, which may be made solid or tubular as desired, the 60 axis of which is preferably at right angles to the bolt 60. The cylindrical post 62 is adapted to extend into the openings 63, having gripping jaws 64, in the resilient clamping member 51, which is split as at 65 to allow movement for clamping ac-

tion, and through an elongated opening 66 in the bolt 46, and when clamped in position is prevented from being withdrawn by the flanged edge 50, of the arm 44, which extends into annular grooves 67, formed on 70 the cylindrical post 62.

The head 48 of the bolt 46, engages the recess 47 in the bracket arm 44 and the body of the bolt extends through openings 45, 52 and 68 formed in the bracket arm 44, resilient 75 clamping member 51 and washer 56 respectively. The end of the bolt is screw threaded as at 69 upon which is screwed a wing-nut 70, which is prevented from being easily unscrewed when in a clamped position by the locking washer 71.

In this type of joint when the wing-nut 70 is screwed tight upon the threaded end 69, of the bolt 46, the beveled surfaces 49, 53, 54 and 55 are forced into frictional contact with each other, at the same time the jaws 64, on the resilient clamping member 51, are forced into gripping engagement with the cylindrical post 62, thereby holding all of the parts rigidly in position, and to 90 allow for the resilient clamping member a greater lateral spring action and also to allow for wear, a slight space 72 is left between the central portion of the resilient clamping member 51 and the washer 56, as 95 clearly shown in Figure 16, of the drawings.

In Figure 15 the resilient clamping member 5 is the same as that described for Figures 1 to 12, being split as at 6, with cylindrical openings 7, beveled face 8, flanged edge 9, opening 18, and clamping jaws 26.

Upon the beveled face 8 of the resilient clamping member 5, is mounted the bracket arm 44, having the opening 45 surrounded by a beveled surface 49 for contacting with the beveled face 8 of the resilient clamping member 5.

73 indicates a clamping bolt, having a head 74 engaging the flanged edge 9 of the resilient clamping member 5, which extends through openings 18 and 45 in the clamping member and bracket arm respectively, and is screw threaded at 75 for receiving the clamping nut 76, which can be locked in 110 position by means of the lock washer 77.

In this joint the cylindrical post 62 extends into the opening 7 of the resilient clamping member 5, and is held in position when the clamping nut 76 is screwed tight upon the bolt by means of the clamping jaws 26 gripping the sides of the cylindrical post 62, which also has a catch 78 working in a longitudinal groove 79, for preventing the joint from working off the end of the cylindrical post.

12 In Figure 17 I have illustrated the bolt 80 as serving the purpose of a resilient clamping member, being split longitudinally as at 81, and having a head 82 with a cylindrical opening 83, for receiving the 13

cylindrical post 62. The inner sides of the head 82, of the bolt 80 are beveled as at 84, for engaging with the beveled side 85 of a washer 86. The body of the bolt is screw-threaded throughout its length and has mounted thereon the washer 86, bracket arm 87, which is perforated as at 88, lock washer 89 and wing-nut 90. In this joint the side faces of the bracket arm 87 are flat, the frictional contact being produced by the sides of the washer 86, which forces the arc-shaped jaws 91 of the opening 83 in gripping engagement with the cylindrical post 62, at the same time the flat sides of the bracket arm 87 are gripped firmly between the lock washer 89 and the washer 86.

In Figure 18 I have shown another modification in which the bolt serves the purpose of the resilient clamping member. In the figure 92 indicates the clamping bolt split longitudinally as at 93, with an elongated opening therein as at 94, beveled head 95 and with a screw-threaded reduced end 96. 97 indicates the movable bracket arm, having an opening 98 with beveled edge 99 for frictionally engaging the head 95 of the bolt 92. The clamping washers are indicated as at 100, each having arc-shaped jaws 101 for engaging the cylindrical post 62, which is clamped between them and is held in position by means of the wing-nut 102 and lock washer 103 as will be readily understood by referring to the drawing.

It will be noted in all of the joints above described I have provided for longitudinal and axial adjustment by means of a single clamping bolt and nut.

Although I have shown and described my invention in considerable detail, I do not wish to be limited to the exact and specific details shown and described, but may use such substitutions, modifications or equivalents thereof as are embraced within the scope of my invention or as pointed out in the claims.

Having thus described my invention, what I claim and desire to secure by Letters Patent is:—

1. In a flexible joint, comprising a pair of arms, a resilient clamping member and a coacting clamping member mounted thereon, a swivel connection between the clamping members, and a single means for holding the pair of arms and clamping members in frictional contact with each other.

2. In a flexible joint, comprising a pair of arms, a resilient clamping member and a coacting clamping member mounted thereon, said clamping members being engaged with each other for rotation on an axis intersecting said arms, and a single means for increasing or decreasing frictional engagement between said pair of arms and clamping members.

3. In a flexible joint, comprising a pair

of arms, a resilient clamping member adapted to engage one of said arms, a coacting clamping member for engaging the other arm, a swivel connection between the two clamping members, and a single means for increasing or decreasing frictional engagement between said pair of arms and clamping members.

4. In a flexible joint, comprising a pair of arms, a resilient clamping member engaging one of the arms, a clamping member frictionally engaging the resilient clamping member, for supporting the other arm, a swivel connection between the clamping members, and a single means for increasing or decreasing frictional engagement between said pair of arms and clamping members.

5. In a flexible joint, comprising a pair of supporting arms, a single clamping member engaging one of the arms, a clamping member frictionally engaging the single clamping member for supporting the other arm, a swivel connection between the clamping members, and a single means for increasing or decreasing frictional engagement between said pair of arms and clamping members.

6. In a flexible joint, comprising a pair of supporting arms, a single clamping member engaging and supporting one of the arms, a clamping device mounted upon and frictionally engaging the single clamping member for supporting the other arm, a swivel connection between the clamping members, and a single means for increasing or decreasing frictional engagement between said clamping members and arms.

7. In a flexible joint, comprising a resilient clamping member, an arm extending through the resilient clamping member, an opening in the side of the resilient clamping member at right angles to the axis of the arm passing through the resilient clamping member, a bolt having its head retained in the resilient clamping member and extending through an opening in the side of the resilient clamping member with an outwardly extending threaded end, a clamping member mounted upon the bolt for supporting another arm, and a nut on the screw-threaded end of the bolt for increasing or decreasing frictional engagement between said clamping members and arms.

8. In a flexible joint, comprising a resilient split clamping member, an arm extending through the resilient split clamping member, an opening in the side of the resilient clamping member at right angles to the axis of the arm passing through the resilient split clamping member, an annular beveled outer face on the resilient split clamping member, a bolt having its head retained in the resilient split clamping member and extending through the opening in the side

- of the resilient split clamping member with an outwardly extending threaded end, a pair of clamping members upon the bolt for clamping another arm between them, and a nut on the screw-threaded end of the bolt for increasing or decreasing frictional engagement between said clamping members and arms.
9. In a flexible joint, comprising a resilient split clamping member, an arm extending through the resilient split clamping member, an opening in the side of the resilient split clamping member at right angles to the axis of the arm passing through the resilient split clamping member, the resilient split clamping member being formed around its side opening with an inner flanged edge and an outer annular beveled surface, a bolt having its head retained by the flanged edge of the resilient split clamping member and extending through the opening in the side of the resilient split clamping member with an outwardly extending threaded end, clamping means mounted upon the bolt and adapted to clamp another arm, and means on the screw-threaded end of the bolt for simultaneously increasing or decreasing frictional engagement between said clamping members and arms.
10. In a flexible joint, comprising a resilient split clamping member, an arm extending through the resilient split clamping member, jaws on the resilient split clamping member for engaging said arm, an opening in the side of the resilient split clamping member at right angles to the axis of the arm passing through the resilient split clamping member and being formed around its side opening with an inwardly extending flanged edge and an outer annular beveled surface, a bolt having its head retained by the inwardly extending flanged edge of the resilient split clamping member and extending through the opening in the side of the resilient split clamping member, the outer end of said bolt being screw-threaded, a pair of washers mounted upon the bolt and adapted for receiving and holding another arm, and a nut on the screw-threaded end of the bolt for simultaneously increasing or decreasing frictional engagement between said clamping members and arms.
11. In a flexible joint, comprising a resilient split clamping member, an arm extending through the resilient split clamping member, jaws on the resilient split clamping member for engaging said arm, an opening in the side of the resilient split clamping member at right angles to the axis of the arm passing through the resilient split clamping member, said resilient split clamping member being formed around its side opening with an inwardly extending flanged edge and an outer annular beveled surface, a bolt adapted to have its head retained by the inwardly extending flanged edge of the resilient split clamping member and extending through the opening in the side of the resilient split clamping member, the outer end of said bolt being screw-threaded, a pair of washers provided with arc-shaped gripping jaws mounted upon the bolt and adapted to receive and hold another arm, and one of said washers having a beveled side face for engaging the annular beveled surface around the side opening on the resilient split clamping member, and a nut on the screw-threaded end of the bolt for simultaneously increasing or decreasing frictional engagement between said clamping members and arms.
12. In a flexible joint, comprising a resilient clamping member, an arm extending through the resilient split clamping member, jaws on the resilient split clamping member for engaging said arm, an opening in the side of the resilient split clamping member at right angles to the axis of the arm passing through the resilient split clamping member, the said resilient split clamping member being formed around its side opening with an inwardly extending flanged edge and an outer annular beveled surface, a bolt adapted to have its head retained by the inwardly extending flanged edge of the resilient split clamping member, the said bolt having a narrow neck portion extending through the opening in the side of the resilient split clamping member, the outer end of the said bolt being screw-threaded, a pair of washers provided with arc-shaped gripping jaws mounted upon the bolt, said gripping jaws on the washers being in alignment with a perforation in the bolt and adapted to receive and hold another arm between the gripping jaws of the washers, said arm passing through the perforation in the bolt, one of the washers having a beveled side face for engaging the annular beveled surface around the side opening on the resilient split clamping member, and a nut on the screw-threaded end of the bolt for simultaneously increasing or decreasing frictional engagement between said clamping members and arms.
13. In a flexible joint, comprising a resilient split clamping member, an arm extending through the resilient split clamping member, jaws on the resilient split clamping member for engaging said arm, an opening in the side of the resilient split clamping member at right angles to the axis of the arm passing through the resilient split clamping member, the said resilient split clamping member being formed around its side opening with an inwardly extending flanged edge and an outer annular beveled surface, a bolt adapted to have its head retained by the inwardly extending flanged edge of the

resilient split clamping member, the said bolt having a narrow neck portion extending through the opening in the side of the resilient split clamping member, the outer 5 end of the bolt being screw-threaded, a pair of washers provided with arc-shaped gripping jaws mounted upon the bolt, said gripping jaws on the washers being in alignment with a perforation through the bolt 10 and adapted to receive and hold another arm between the gripping jaws of the washers, said arm passing through the perforation in the bolt, a beveled side face on one of the washers for engaging the annular beveled 15 surface around the side opening on the resilient split clamping member, a spline between the washers and the bolt, and a nut on the screw-threaded end of the bolt for simultaneously increasing or decreasing 20 frictional engagement between the clamping members.

14. In a flexible joint, comprising a resilient clamping member having a cylindrical opening therein, an arm extending into 25 the cylindrical opening, arc-shaped gripping surfaces within the cylindrical opening adapted to engage the arm, a split projection on one side of the resilient clamping member, an opening in the split side 30 projection, at right angles to the cylindrical opening, the said split projection being formed around the said opening with an inwardly extending flanged edge and an outer annular beveled surface, a bolt having its 35 head retained by the inwardly extending flanged edge of the split projection, said bolt extending through the opening in the split projection and screw-threaded on its outer end, a coacting clamping member having 40 a beveled face mounted upon the annular beveled surface of the resilient clamping member and retained in position by the bolt, and a nut on the screw-threaded end of the bolt for simultaneously increasing 45 or decreasing the frictional engagement between the beveled surfaces of the clamping members.

15. In a flexible joint, a pair of adjustable arms, a resilient clamping member for engaging one of the arms, a bolt having its 50 head secured in the resilient clamping member with an outwardly extending threaded end, a coacting clamping member mounted upon the bolt for engaging the other arm, said clamping members being engaged with each other for rotation on an axis intersecting both of said arms and in alignment therewith, and a nut on the screw-threaded 55 end of the bolt for increasing or decreasing frictional engagement between said clamping members.

16. In a flexible joint, comprising a pair of adjustable arms, a resilient clamping member for engaging one of the arms, means

for forcing the resilient clamping member 65 into frictional engagement with said arm, a bolt provided with a head adapted to be secured in the resilient clamping member, said bolt having an outwardly extending threaded end, a coacting clamping member mounted 70 upon the bolt for engaging the other arm, a swivel connection between the resilient clamping member and the coacting clamping member, said clamping members being engaged with each other for rotation on an axis 75 intersecting both of said arms and in alignment therewith, and a nut on the screw-threaded end of the bolt for increasing or decreasing frictional engagement between 80 said clamping members.

17. In a flexible joint, comprising a pair of supporting arms, a single clamping member having a cylindrical opening with arc-shaped jaws engaging one of the arms, said resilient clamping member being split at its 85 side and having an opening formed therein, the clamping member having a flanged inner surface and an outer beveled face surrounding said opening, a bolt having a head retained by the flanged inner surface, a 90 clamping member mounted on the bolt and having a beveled surface frictionally engaging the single clamping member for supporting the other clamping member and forming a swivel connection between the clamping 95 members, means for increasing or decreasing frictional engagement between said clamping members, and means for forcing the arc-shaped jaws of the single clamping member at right angles to the bolt into or out of engagement with the arm.

18. In a flexible joint, comprising a pair of supporting arms, a single clamping member having a cylindrical opening with arc-shaped jaws engaging one of the arms, said 105 resilient clamping member being split at its side and having an opening formed therein, a flanged inner surface and an outer beveled face surrounding said opening, a bolt having a head retained by the flanged inner surface, and extending outwardly therefrom with an outer threaded end, clamping washers mounted on the bolt, one of said washers having a beveled surface frictionally engaging the beveled face of the single clamping 115 member for supporting the other clamping arm and forming a swivel connection between the clamping members, and a nut screwed upon the threaded end of the bolt for increasing or decreasing frictional engagement 120 between said clamping members and arms and for forcing the arc-shaped jaws of the single clamping member at right angles to the bolt into or out of engagement with the arm.

In witness whereof I hereunto affix my signature.

ELMER S. SEAVEY.
